UNITED STATES PATENT OFFICE.

ABRAM LE GALLEZ, OF ALBANY, NEW YORK.

DESIGN FOR A TYPE-WRITING-MACHINE-ERASER HOLDER.

SPECIFICATION forming part of Design No. 32,988, dated July 24, 1900.

Application filed October 27, 1899. Serial No. 735,001. Term of patent 7 years.

To all whom it may concern:

Be it known that I, ABRAM LE GALLEZ, a citizen of the United States, residing in the city and county of Albany, State of New York, have **5** invented and produced a new and original Design for a Type-Writing-Machine-Eraser Holder, of which the following is a specification, reference being had to the accompanying drawing, forming a part thereof.

• The figure is a perspective view of the type-writing-machine-eraser holder.

The leading features of my design consist of a substantially V-shaped body, as shown in the accompanying drawing, the arms of which **5** terminate abruptly at their lower ends and are joined together by a narrow flat portion. Each of the arms is thin and flat, and one of them, A, is straight except at its upper end,

which is curved outward, as shown at B. The lower end of the other arm stands parallel **20** with the arm A for a short distance, and it then diverges outward, as shown at D. Its upper portion is bent inward at short angles and then outward, as shown at C, and is perforated. **25**

Having described my invention, what I claim as new, and desire to secure by Letters Patent, is—

The design for a type-writing-machine-eraser holder, as herein shown and described. **30**

Signed by me at Albany, New York, this 20th day of October, 1899.

ABRAM LE GALLEZ.
